LOW AIR PRESSURE SPRINKLER SYSTEM

Harry N. Rider, Youngstown, Ohio, assignor to
 "Automatic" Sprinkler Company of America,
 Youngstown, Ohio, a corporation of Delaware

Application March 16, 1942, Serial No. 434,858

4 Claims. (Cl. 169—17)

This invention relates to an automatic sprinkler system for the control of fire and particularly to a system fully automatic in operation and wherein a slight reduction of low pressure air in the sprinkler system results in the sprinkler system's going into operation.

The principal object of this invention is the provision of an automatic sprinkler system which will operate efficiently with an air pressure carried therein substantially lower than pressures heretofore generally carried in dry pipe systems.

A further object of the invention is the provision of a low air pressure sprinkler system employing in combination a dry pipe valve which responds rapidly to decreases in air pressures; eliminating the necessity of employing quick acting devices such as accelerators or exhaustors, and a water powered airpump which serves to maintain suitable air pressure in the piping of the sprinkler system.

A further object of the invention is the provision of a sprinkler system incorporating the dry pipe valve which will make it possible to maintain a relatively low air pressure in the piping of the sprinkler system which will result in water reaching the sprinklers immediately without the heretofore unavoidable delays occasioned by the escape of a considerable volume of air from the piping of the sprinkler system, and which relatively low air pressure is automatically maintained between predetermined maximum and minimum pressures by a water powered air pump which is capable of maintaining a suitable air pressure in the system during the intervals between periodic water powered operation.

A further object of the invention is the provision of a sprinkler system wherein the main valve is automatically primed and wherein condensate and liquid residue are automatically drained.

A further object of the invention is the provision of a sprinkler system having a dry pipe valve therein incorporating electric switches which are actuated in such a manner that an alarm is given in advance of the opening of the dry pipe valve and the subsequent delivery of water by the sprinkler system.

With the foregoing and other objects in view which will appear as the description proceeds, the invention resides in the combination and arrangement of parts and in the details of construction hereinafter described and claimed, it being understood that changes in the precise

embodiment of the invention herein disclosed, can be made within the scope of what is claimed without departing from the spirit of the invention.

5 The invention is illustrated in the accompanying drawings, wherein:

Figure 1 is an elevational view of a low air pressure sprinkler system with parts broken away and illustrating a complete system formed in accordance with the present invention.

Figure 2 is a side elevational view of the low air pressure sprinkler system shown in Figure 1.

Figure 3 is a cross sectional elevation of the dry pipe valve and associated operating means which forms a part of the low air pressure sprinkler system.

Figure 4 is a cross sectional side elevation taken approximately on lines 4—4 of Figure 3 illustrating the dry pipe valve actuating means, the dry pipe valve body not being shown in Figure 4.

Figure 5 is a cross sectional view taken on approximately lines 5—5 of Figure 2 illustrating the details of construction of the water powered air pump which forms a portion of the sprinkler system.

Figure 6 is a cross sectional elevation of an alarm valve.

Figure 7 is a cross sectional side elevation of 30 a velocity ball check valve a part of the low air pressure sprinkler system shown in Figure 1.

By referring to the drawings and Figures 1 and 2 in particular, it will be observed that the low air pressure sprinkler system comprises a main fluid supply pipe 10 for supplying fire extinguishing fluid under pressure provided with a manual gate valve 11 and with an automatically operating dry pipe valve 12. The fluid supply is conducted from the dry pipe valve through a riser 13 having suitable branch pipes 14 which in turn are equipped with sprinklers 15. The branch pipes 14 lead to the different fire zones of the structure in which the low air pressure sprinkler system is installed.

45 The gate valve 11 is controlled by means of a hand wheel 16 and valve operating shaft placed within a yoke 17 of the gate valve 11. The gate valve 11 is normally open so that the fluid supply entering the system through the pipe 10 is actually controlled by the dry pipe valve 12 which dry pipe valve 12 is shown in detail in Figure 3 of the drawings. The dry pipe valve 12 includes a latched clapper in its construction and at such times as the sprinkler system is ready for 50 operation, but not in actual operation delivering

fire extinguishing fluid, the complete system above the clapper of the dry pipe valve 12, comprising the riser 13 and any and all branch pipes 14 is filled with air under low pressure which is retained in the system as the sprinklers 15 are normally closed. The low air pressure in the system is supplied by a water powered air pump the body portion of which is indicated in Figures 1 and 2 by the numeral 18. In Figure 2 of the drawings, the air pump's mechanism enclosing housing is indicated by the numeral 19 and a water leg included in the air pump's construction and essential thereto is indicated by the numeral 20. A secondary water leg 21 extends above the body member 18 of the water powered air pump and the upper most end thereof is provided with an L 22 which forms an overflow passage for water rising upwardly through the secondary water leg 21. A funnel 23 communicating with a drain pipe 24A conveys the overflowing water to a main drain pipe 24 which in turn is connected with the dry pipe valve body 12 below the clapper therein so that the system may be drained therethrough after it has been in operation.

The water powered air pump 18 illustrated in Figures 5 and 6 of the drawings, supplies the sprinkler system with air under relatively low pressure and its mode of operation in supplying the said air will be developed herein. It will be seen that the water powered air pump 18 is supplied with fluid through a pipe 25 which communicates with the main fluid supply through the gate valve 11, communicating with the gate valve 11 below the gate therein, and is provided with a sediment trap 26 to insure the delivery of clean fluid to the air pump 18. Still referring to Figure 1, it will be seen that a pipe 27 communicates with the water powered air pump 18 and extends upwardly therefrom terminating in a pressure gauge. Two branch pipes communicate with the pipe 27 the lowermost one of which is indicated by the numeral 28 also communicates with the interior of the dry pipe valve 12 above the clapper therein through a fitting 29. A velocity ball check valve is positioned in the pipe 28 and is indicated by the numeral 30. This velocity ball check valve 30 permits the free flow of air from the body 18 of the air pump into the body 12 of the dry pipe valve, and permits condensate and residue liquid in the system above the fitting 29 to drain therethrough into the air pump 18. By referring to Figure 2 of the drawings, a cross sectional side elevation of the velocity ball check valve 30 may be seen to comprise a pair of valve bodies 30 and 30A threadably engaging one another and containing a ball 30B which is adapted to normally remain in the position shown and move responsive to abnormal pressure from the left hand side of the valve seat 30C formed in the body 30. The valve seat 30C is provided with a relatively small notch 30D which causes the velocity ball check valve to open faster when abnormal pressure against the same is released. The seat portion 30C of the valve is positioned opposite the pressure inlet which in this disclosure comprises the fitting 28 communicating with the dry pipe valve 12 above the clapper thereof. The uppermost of the two pipes communicating with the upwardly extending pipe 27 is indicated by the numeral 31 and also communicates with the actuating portion of the dry pipe valve indicated by the numeral 32. Thus air under pressure established by the air pump in the body portion 18 thereof flows through the

75 pipes 27 and 28 into the dry pipe valve body 12 and upwardly into the system through the riser 13 and the other associated parts. In order that an alarm may be given when the system goes into operation as in extinguishing a fire, a relatively small alarm valve 33 communicates with the pipe 28 adjacent the fitting 29 which communicates with the interior of the dry pipe valve 12. When the clapper in the dry pipe valve 12 opens, water under pressure enters the same and flows upwardly through the riser 13 and outwardly through the pipe 28 and forces open the alarm valve 33 from whence it travels by means of pipes 34 and 35 to a pressure switch 36 and if desired through a continuation of the pipe 35 indicated in the drawings by the numeral 35A to a water motor alarm. The velocity ball check valve 30 prevents water from flowing through the pipe 28 into the pipe 27 and the air pump body 18 as the velocity of the water entering the velocity ball check valve 30 actuates the same. The pressure switch 36 may be any commercially available pressure operated switch which may obviously actuate any desirable alarm connected therewith. It will also be seen that connecting with the fitting 29 on the dry pipe valve 12 and extending upwardly therefrom there is a pipe 37 provided with a sprinkler 37A which when the system is in operation will serve to protect the valve and pump assemblies from fire.

30 It will be seen that a dry pipe system has been provided wherein water from the supply source is prevented from entering the system by means of the dry pipe valve 12 and that the system itself is filled with air under low pressure which is supplied and maintained by the water powered air pump 18.

35 The dry pipe valve and its actuating mechanism are dependent upon a variation in the air pressure in the sprinkler system for operation and the following is a detailed description of the dry pipe valve 12 and its actuating mechanism which may be seen by referring to Figures 3 and 4 of the drawings.

40 45 By referring to the drawings and Figure 3 in particular it will be seen that the dry pipe valve comprises a body 12 in which a water inlet is indicated at 38. In order that the water inlet 38 may be effectively separated from the remainder of the valve body, an annular shoulder 39 provided with a seat ring 40 adapted to receive a clapper 41 serves to effectively control the admission of water into the valve body from the water inlet 38. A suitable rubber facing 42 is affixed to the clapper 41 by means of a clamping ring 43 which in turn is affixed to the clapper 41 by means of a plurality of cap screws.

50 55 The clapper 41 is formed with a pair of hinge arms 44 adapted to pivot about a hinge pin 45 so as to effectively hinge the clapper in relation thereto. The hinge pin 45 is carried on suitable bushings positioned in the valve body 12. In order that the clapper 41 will remain in closed position on the water inlet 38 and thus prevent

60 65 the passage of water through the valve, a latch mechanism is positioned within the valve body and adjacent to a shoulder 46 formed on the clapper 41. The latch mechanism comprises a latch 47 pivoted to the valve body by means of a latch hinge pin 48 so that horizontal movement imparted to the lower end of the latch 47 results in moving it from its seat on the shoulder 46 of the clapper 41 thus effectively releasing the clapper 41 and permitting water in the water inlet 38 to raise the clapper 41 and flow

through the valve. Still referring to the latch mechanism it will be seen that the latch 47 has an anti-reseating portion 49 pivoted thereto and adapted to prevent the clapper 41 from reseating. In order that the anti-reseating latch 49 will remain in effective operating position, a latch spring 50 is utilized which serves to position the anti-reseating latch portion 49 in operative relation to the clapper 41 at all times.

In order that movement may be imparted to this latch 47 so as to result in the opening of the clapper 41, a latch link 51 is pivoted at its innermost end to the latch 47 by means of a link pin 52. This latch link 51 passes centrally through and is affixed to a circular latch link diaphragm 53 which is positioned in a water tight manner across an opening 54 in the side of the valve body 12 and thus permits the transmittal of movement through the latch link 51 while effectively closing the opening 54 in the valve body 12. The latch link 51 passes through an opening in the diaphragm 53 and is affixed therein in a water tight manner by means of a nut 55 threaded thereon so as to oppose an annular shoulder 56 formed on the latch link 51. A portion of the latch link extends outwardly from the annular shoulder 56 and comprises in effect a T headed connection section adapted to receive in a movable manner a latch arm 57 which is part of a valve actuating mechanism which comprises a vertically positioned actuating mechanism box 58 bolted by means of bolts 59 to the valve body 12 at a point thereon adjacent the opening 54 thereof so that its mechanism effectively imparts movement to the latch link 51.

The latch arm 57 is pivoted by means of a hinge pin 60 to the box 58 and is adapted to impart movement to the latch link 51. In order that the latch arm 57 may receive movement suitable for actuating the latch link 51 and, in turn, the latch 47, an end 61 thereof is pivoted by means of a pin 62 to the lowermost end of a vertically positioned guide rod 63.

By referring to Figure 4 of the drawings it will be seen that the uppermost end of this guide rod 63 is slideably positioned within a sleeve 64 which is in turn carried upon a portion 65 of a release frame 66. A pin is positioned through the guide rod 63 so as to limit the upward movement thereof which might otherwise interfere with the action of the releasing mechanism. A weight 67 having a centrally positioned opening 68 therein is positioned on the rod 63 so as to be slideable vertically thereof. In order that the weight 67 may be maintained in elevated position as shown in the drawings, a barbed shaft 69 is affixed thereto in a flexible manner by means of a retaining plate 70 and a coil spring 71. The barbed shaft 69 is retained in position by means of a barb latch 72 pivoted to a bracket on the portion 65 of the release frame 66 by means of a pin 73. The opposite end of the barb latch 72 tapers to a point adapted to be retained beneath a ledge 74 formed on a disk affixed to a diaphragm 75 which is in turn positioned on and over an opening formed by the release frame 66. A coil spring 76 is positioned between the inner side of the diaphragm 75 and an adjacent section 77 of the release frame 66 so that the coil spring 76 tends to move the diaphragm 75 outwardly so as to release the pointed end of the barb latch from beneath the ledge 74 of the disk positioned thereon. By referring to Figure 3 it will be seen that the section 77 referred to is tubular in shape and threadably positioned within a threaded opening in the por-

tion 65 of the release frame 66. In order that an air pressure chamber may be formed adjacent the diaphragm 75, a diaphragm cap 78 is bolted to the release frame 66 and the box 58 adjacent the diaphragm 75. A gasket 79 is positioned between the diaphragm cap and the release frame 66 to insure a tight joint and the diaphragm cap 78 is provided with the threaded opening 32 adapted to receive and communicate with the piping 31 and 27 through which communication is established with the body 18 of the air pump and with the valve body 12 so that the pressure chamber formed adjacent the diaphragm 75 will receive and retain air under pressure equal to that in the valve body 12 and sprinkler system.

In operation the air under pressure in the piping of the sprinkler system will be released upon the opening of any given sprinkler thus resulting in a rapid decrease of air pressure within the diaphragm cap 78. This decrease in air pressure results in the coil spring 76 moving the diaphragm 75 outwardly into the area within the diaphragm cap and thus release the barb latch 72 from beneath the ledge 74 of the diaphragm. When this occurs the barbed shaft 69 and the weight 67 drops downwardly along the guide rod 63 and the weight 67 strikes the end 61 of the arm 57 thus effectively moving the same. This action moves the latch link 51 outwardly together with the latch 47 which results in the unlatching of the clapper 41.

In order that the low pressure dry pipe valve may be operated manually if desired, as for example, at such times as a fire is observed in its early stages, mechanism has been incorporated to permit the manual release of the weight 67 which will effectively cause the dry pipe valve to be unlatched and permit the sprinkler system to be filled with water. By referring to Figure 4 wherein this mechanism is illustrated more clearly, it will be seen that a manual release arm 80 is pivoted to a bracket formed on a portion 65 of the release frame 66 by means of a pin 81 and that its upper end forms an operating lever 82 shaped to fit under an edge of the barb on the barbed shaft 69 in opposite relation to the barb latch 72. A tension spring 83 positioned about the pin 81 serves to hold the manual release arm and operating lever 82 in position. By referring to the lower end of the arm 80 it will be seen that a rod 84 is attached thereto by suitable pivot means and carries on its outermost end a push button 85 which is slideably positioned within an opening in a cover portion 86 of the actuating mechanism box 58. It will be seen that by pushing the push button 85 inwardly the arm 80 turns or pivots upon the pin 81 and effectively releases the operating lever 82 from beneath the barbed shaft 69 thus effectively permitting the weight to drop and actuate the valve.

Still referring to Figure 4 it will be seen that electric switches are incorporated with the valve releasing mechanism and comprises a pair of mercury switches 87 positioned in suitable clamps 65 on a tiltable base 88 which is pivoted at its outermost end to a terminal block 89. It will be seen that as long as the weight 67 is in its uppermost position as shown in the drawings, the base 88 carrying the mercury switches 87 will remain tilted and effectively keep the switches open and that when the weight 67 drops the base 88 will follow that movement a relatively short distance thus effectively closing the circuit through the mercury switches which tilt into closed position. It will be obvious that any other

type of electric switch may be utilized so as to be operative at such times as the weight 67 is released by the valve operating mechanism. Thus an electrical alarm may be given prior to the actual opening of the dry pipe valve 12 which is of considerable value in the event that the water supply to the dry pipe valve has been interrupted.

Having thus described the specific dry pipe valve and actuating mechanism used as a component part of the low air pressure sprinkler system, the following concerns the water powered air pump 18 and comprises a specific description of the operating structure thereof.

By referring to Figure 5 of the drawings, it will be seen that the air pump comprises a body member 18 on one side of which there is positioned a mechanism enclosing housing 19 which in turn is secured to the body member 18 by means of bolts 90 functioning through openings in the flange 91 formed on the housing 19. The housing 19 is positioned over a large opening in the body member 18. Positioned in this large opening there is a pressure responsive valve operating mechanism.

By referring again to Figure 1 of the drawings, it will be observed that the bottom of the body member 18 is provided with an opening in which is positioned the water leg 20 which is provided at its lower extremity with a cap 93 which in turn is provided with a plugged opening 94. Positioned vertically through the body member 18 and extending downwardly within the water leg 20 there is a secondary tubular water leg 21 which terminates short of the bottom of the water leg 20 and emerges through an opening in the top of the body member 18 and is provided with an L 22 which forms the overflow passage for water rising upwardly through the secondary water leg 21.

In order that water and air may be introduced into the body member 18 in order that the air pump action may take place, a jet pump chamber 95 is affixed by means of bolts 96 to one side of the body member 18 as may be seen in Figure 2, and by referring to Figure 5 and to the right hand portion thereof wherein a cross sectional detailed view of the jet pump is shown it will be seen that water entering by way of an orifice 97 is directed, at such times as a water control valve 98 is open, through a jet 99 and into a Venturi jet pump 100 by which action it causes a quantity of air to be delivered therewith into the body member 18 of the pump by way of an upwardly extending communication channel 101 which in turn forms a part of the jet pump housing 95A and is bolted to the body member 18 by bolts 96. Air is introduced into the Venturi jet pump through an orifice 102 in the bottom of the jet pump chamber 95. When the valve 98 is open, and water enters from the pipe 25, the resultant action of the water passing into the Venturi jet pump will be the introduction of a substantial quantity of air into the body member 18 along with the water. The water introduced will flow downwardly through the water leg 20 which communicates with the bottom portion of the body member 18 and subsequently rise within the secondary water leg 21 to the uppermost end thereof which is substantially above the body member 18 from which it will be discharged.

In order that the air introduced into the body member 18 may be retained so that a workable air pressure may be built up in the piping of the sprinkler system associated therewith by

way of the pipes 27 and 28, a diaphragm 103 which carries a centrally positioned piston like structure 104 is positioned in the large opening between the body member 18 and the housing

5 19 the outer extremity of the diaphragm 103 being securely positioned between the flange of the body member 18 and the flange 91 of the housing 19. Thus air introduced into the body member 18 is restricted thereto by the flexible diaphragm 103 and its piston like structure 104 which forms a flexible water and air tight seal.

It will thus be observed that when, due to the continuous operation of the Venturi jet pump, a satisfactory air pressure has been built up within 15 the body member 18 of the pump and the associated piping of the sprinkler system, the normal tendency of the diaphragm 103 will be to move outwardly into the adjacent housing and in order that this movement may be suitably utilized

20 to control the introduction of water into the Venturi jet pump, means has been associated with the diaphragm 103 and the water control valve 98 for either opening or closing the valve 98 in accordance with the position of the dia-

25 phragm 103 and its piston like structure 104 which in turn is adjustably opposed by a coil spring 105 with respect to a tubular adjustment member 106 which is threadably positioned in a threaded opening in the housing 19. The tubular adjustment member 106, threadably positioned in the opening in the housing 19, permits the tension on the spring 105 to be varied so that any desirable air pressure may be maintained within the body member 18. In order that the move-

35 ment of the piston like structure 104 carried on the diaphragm 103 will result in movement of the water control valve 98, a rod 107 is affixed in an opening formed in a centrally located boss 108 on the piston like structure 104, and extends

40 outwardly therefrom and terminates in a pivot structure 109 connected to an end of a secondary rod 110 which engages a part of the water control valve 98 by reason of an end thereof functioning within a suitable opening in the water control valve 98. The rod 110 is pivoted to an adjacent portion of the jet pump chamber 95 by a pivot 111. Immediately surrounding the rod 110 and pivot 111 and forming a flexible water tight seal there is a diaphragm gland 112 which is positioned between a bracket 113 located within the housing 19 and a portion of the jet pump chamber 95 so that the rod 110 passes therethrough in a movable manner.

55 In order that the action of the water control valve 98 may be controlled and adjusted with respect to the air pressure built up within the body member 18 by the pump action, spring tensioned adjustment means have been provided to limit the movement of the rod 107, which is moved by the diaphragm 103 and its piston like structure 104, and comprises a pair of roller carrying arms 114 pivoted at 115 to a bracket 116 which is in turn affixed to the housing 19. The rollers carried on the roller arms 114 engage the rod 107

60 and, as the rod 107 is provided with an irregular surface, tension brought to bear between the opposite ends of the roller arms 114 by means of an adjustably mounted spring 117 effectively controls the movement of the rod 107 until a desirable pressure against the diaphragm 103 has been established. The spring 117 is adjusted with respect to the roller arms 114 by means of an adjustment screw 118.

65 It will thus be observed that at such times as the air within the body member 18 reaches a

predetermined pressure the diaphragm 103 and the piston like structure 104 will sufficiently compress the spring 105; to enable the rods 107 and 110 to close the water control valve 98, and that when such action has taken place the water which has been overflowing through the L 22 on the upper end of the secondary water leg 21 will, as the air pressure within the body member 18 of the pump diminishes, drop within the secondary water leg 21 in direct relation thereto and thus serve to maintain the air pressure within the body member as the column of water rises in the water leg 20. This action continues until the water within the secondary water leg 21 has dropped to a level where it can no longer effectively move the column of water upwardly within the water leg 21. From this point on diminishing air pressure within the body member 18, as may be occasioned by leakage in the sprinkler system, results in the spring 105 moving the diaphragm 103 and the piston like structure 104 into the body member 18 and thus effectively opening the water control valve 98 which completes the cycle of operation. It will thus be seen that the action of this water powered air pump is entirely automatic and that due to the dual water leg construction the air pressure developed by the pump is maintained satisfactorily during the intervals between the actual pumping periods.

It will thus be seen that the sprinkler system and component parts have been designed to achieve certain advantages not heretofore known to the art, one of the principal ones of which is its ability to operate in the event of fire with remarkably low air pressure in the piping of the sprinkler system and to open the dry pipe valve upon a reduction of this low air pressure by only a fraction of a pound. This permits the relatively simple and responsive air pump to be used in the system which is obviously an advantage when compared with the more expensive electric air compressors heretofore necessary to maintain relatively high pressures in the piping of the sprinkler system. Another advantage resulting through the use of extremely low air pressure in the piping of the sprinkler system is in that the air when put into the system will not be of high temperature and, therefore, the condensation in the piping will be much less than has heretofore been the case. This will tend to eliminate broken pipes caused by the freezing of condensate in cold weather. Another advantage resulting from the low air pressure carried in the piping of the sprinkler system is that the fanning of the fire with compressed air escaping from sprinklers is eliminated as the relatively small quantity of air in the piping of the system escapes rapidly and permits the water to reach the sprinklers more quickly. A low air pressure sprinkler system formed in accordance with this invention may be tested at frequent intervals, and particularly the dry pipe valve thereof without filling the piping of the sprinkler system with water, as the operating mechanisms except for one latch are external parts and further, the priming of the valve of the system occurs when the water supply in the water supply pipe 10 comes in contact with the under side of the clapper 41 and there are, therefore, no external pipe connections for priming purposes. It will also be seen that the sprinkler system may be reset for use after operation in a relatively short time as there is no need of building high air pressure in the piping of the sprinkler system after the fluid in the system has been drained.

therefrom through the drain pipe 24 which is at all other times normally closed at its connection with the dry pipe valve. It will thus be seen that an efficient dry pipe sprinkler system operating upon a fractional drop in the relatively low air pressure carried in the piping of the system has been designed. The system is completely automatic in operation and is not dependent upon electric circuits for operation, as the water supply source maintains the low air pressure in the system, loss of which causes the system to go into operation in controlling a fire upon the opening of any one or more of the sprinklers forming a part thereof. It will also be seen that 10 the low air pressure sprinkler system has an inherent advantage due to the combination of its component parts which advantage comprises the ability of the system to self prime the clapper 41 of the valve 12 and provide for the drainage 15 from the system of condensate or residue liquid after use, which will drain through the velocity ball check valve 39 in a dribble action into the air pump 18 and outwardly therefrom through the secondary water leg 21 and the L 22 due to 20 the air pump's action. The system is thus automatically primed at all times and need not be manually serviced at frequent intervals as is the case with other systems heretofore known in the art. This action is made possible by the combination of the specific air pump 18 with the 25 other portions of the sprinkler system.

By referring to Figure 6, the alarm valve 33 may be seen to comprise a valve seat 120 adapted to be normally closed by a vertically movable 30 valve disk 121 which in turn is part of a valve assembly including a downwardly depending guide 122 which guide has a plurality of vertically positioned openings therein and an upwardly extending rod 123 which telescopically 35 engages a cylinder 124 in the uppermost portion of the alarm valve 33. A coil spring 135 is positioned between a portion of the alarm valve body 33 and the valve assembly disk 121. The tension on the coil spring 135 is adjustable so 40 that the alarm valve may be set to permit the flow of fluid therethrough only at such times as the sprinkler system on which it is installed goes into action delivering fire extinguishing fluid. Fluid enters the alarm valve through an inlet 45 136 and leaves it through an outlet 137.

Having thus described my invention, what I claim is:

1. In a fire extinguishing system having distributing pipes normally containing air at 1½ pounds pressure and an automatic valve in connection therewith controlling the entrance of fluid thereto, the said automatic valve responsive to a reduction in the said air pressure in the distributing pipes, means for supplying air to said system and draining off excess fluid above the priming level of the automatic valve when said automatic valve is closed, said means comprising a Venturi jet type air pump in communication with said automatic valve for maintaining the low air pressure in the said distributing pipes, the said air pump enclosing an air head and including a water column and overflow therefor forming a liquid seal, a velocity ball check valve interposed between the said air pump and the said automatic valve, said velocity ball check valve adapted to permit air to flow from the said pump to the automatic valve and permit drainage to pass from the automatic valve to the said air pump and hence from the sprinkler system, and to close against abnormal pressure

from the automatic valve when the system goes into operation in extinguishing a fire.

2. In a fire extinguishing system having distributing pipes normally containing air at 1½ pounds pressure and an automatic valve in connection therewith controlling the entrance of fluid thereto, the said automatic valve responsive to a reduction in the said air pressure in the distributing pipes, means for supplying air to said system and draining off excess fluid above the priming level of the automatic valve when said automatic valve is closed and means for initiating an alarm when the said draining means becomes inoperative and when the system goes into operation in extinguishing a fire, said means comprising an alarm valve in direct communication with the distribution system side of the said automatic valve and an alarm in communication with said alarm valve, the said alarm valve adapted to open when subjected to a pressure slightly higher than that normally existing in the system.

3. In a fire extinguishing system having distributing pipes normally containing air at 1½ pounds pressure, closed sprinklers on said distributing pipes, an automatic valve in connection with the said distributing pipes for controlling the entrance of fluid thereto, the said automatic valve responsive to a reduction in the said air pressure in the distributing pipes, means in communication with the distribution system side of the automatic valve for supplying air to the said system and for draining off excess fluid above the priming level of the said automatic valve when the automatic valve is closed, said means comprising an air pump having a con-

stant air head and a water column and overflow therefor forming a liquid seal therefor, means for closing off communication therebetween, said means responsive to the entrance of fluid into the said distributing pipes as upon the opening of the said automatic valve.

4. In the fire extinguishing system having distributing pipes normally containing air at 1½ pounds pressure, closed sprinklers on said distributing pipes, an automatic valve in connection with the said distributing pipes for controlling the entrance of fluid thereto, the said automatic valve adapted to be actuated by a reduction in the said air pressure in the distributing pipes, means for supplying air to the said system and draining off excess fluid above the priming level of the automatic valve when the automatic valve is closed, said means comprising a fluid operated jet type air pump in communication with the distribution system side of the automatic valve and including a constant air head and a water column and overflow therefor forming a liquid seal, a velocity ball check valve interposed between said air pump and the said automatic valve for shutting off communication therebetween when the system goes into operation in extinguishing a fire, means for initiating an alarm when the said draining means becomes inoperative, said means comprising an alarm valve in direct communication with the distribution system side of the automatic valve, the said alarm valve adapted to open when subjected to a pressure slightly higher than that normally existing in the said system.
